Primary Examiner — Stacia Cadmus(74) *Attorney, Agent, or Firm* — Pearne & Gordon LLP(57) **CLAIM**

The ornamental design for a wheel, as shown and described.

DESCRIPTION

FIG. 1 is a perspective view of a wheel showing our new invention;

FIG. 2 is a front view thereof;

FIG. 3 is a right side view thereof, a left side view being a mirror image thereof;

FIG. 4 is a top view thereof; and,

FIG. 5 is a bottom view thereof.

The broken line showing of the rear portion of the wheel, the bolts and the center hole is included for the purpose of illustrating environment and forms no part of the claimed design.

1 Claim, 2 Drawing Sheets(56)
